UNITED STATES PATENT OFFICE.

RUSSEL G. WOODWARD, OF WAUKEGAN, ILLINOIS, ASSIGNOR TO UNION SPECIAL SEWING MACHINE COMPANY, OF CHICAGO, ILLINOIS, A CORPORATION OF ILLINOIS.

TRIMMING MECHANISM FOR SEWING-MACHINES.

No. 909,840.

Specification of Letters Patent.

Patented Jan. 12, 1909.

Application filed February 24, 1905. Serial No. 247,158.

To all whom it may concern:

Be it known that I, RUSSEL G. WOODWARD, a citizen of the United States, residing at Waukegan, in the county of Lake, State of Illinois, have invented certain new and useful Improvements in Trimming Mechanism for Sewing-Machines, of which the following is a description, reference being had to the accompanying drawing and to the letters and figures of reference marked thereon.

This invention relates to devices of that class employed for trimming or cutting fabric on sewing machines, and has for its principal object to provide a novel form of trimmer that will exercise a direct shear cut on the fabric at a point close to the line of stitching and opposite the needle, enabling it to trim seams on sharp curves without cutting into the line of sewing; a further object in this connection being to hold the movable shear member or blade laterally against the stationary member, so that the operation will be rendered effective and certain.

A still further object of the invention is to provide a device of this character that may be very quickly and readily adjusted to inoperative position when not required, it being merely necessary to change the position of the movable blade while the stationary blade at the throat plate remains in position without interfering with the ordinary operation of the machine.

With these and other objects in view, as will more fully hereinafter appear, the invention consists in certain features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a rear elevation of a sewing machine provided with a trimmer constructed in accordance with the invention; Fig. 2 is a transverse sectional view of the same on the line 2—2 of Fig. 1; Fig. 3 is a detail perspective view illustrating the principal members of the trimming mechanism, detached;

Fig. 4 is a similar view of the auxiliary frame or bracket; Fig. 5 is a perspective view of the adjustable spring rest; and Fig. 6 is a detail view of the locking device for holding the cutter in inoperative position.

Similar numerals of reference are employed to indicate corresponding parts throughout the several figures of the drawings.

The goose neck *a* is provided with rearwardly extending brackets for the reception of a horizontally disposed shaft 10 that is provided at one end with a rocker arm 11, connected by a link 12 to an eccentric strap that is operated by an eccentric 13 on the main shaft. At the opposite end of the shaft 10 is a rocker arm 14, through which movement is imparted in the manner hereinafter described to the trimming mechanism forming the subject of the present invention.

To the under side of the head is secured a small auxiliary frame or bracket 15, which may in practice constitute an integral part of said frame, and the rear end of this auxiliary frame is preferably connected by a brace 16 to the goose neck. The auxiliary frame is provided with bearings for the reception of a short horizontal shaft 17 on which is pivotally mounted an arm 18, and said arm carries at its front end a cutting blade 19 in the form of a thin metallic strip, the lower edge of which is sharpened to form a cutter and co-acts with a stationary blade 20 at the throat plate to effect the trimming operation. The cutting edge does not extend for the full width of the lower end of the strip 19, a portion of this being extended downward in the form of a finger 21 which plays against the inner face of the stationary cutter, and forms a guide for the said movable blade, so that the cutting edge of the latter may raise to an extent sufficient to permit the entrance of the fabric between the two. The shaft 17 further forms a pivot for the lower end of an angularly bent lever 23, the upper end of which is connected by a link 24 to the rocker arm 14, and bearing against the lever 23 is a spring 25, the opposite end of which bears against an adjustable stop 26 that may be moved for the purpose of adjusting the stress of the spring. The link 24 is of such construction as to permit some lateral movement of

the lever of bar 23 under pressure of the spring. This spring serves to force the lever 18 in the direction of the needle bar and presser bar, and to hold the upper cutting 5 blade 19 firmly against the cutting blade 20, thus insuring positive cutting action without regard to the thickness of the fabric. Pivoted to the lever 23 is an arm or link 28, the lower end of which has a recess for the 10 reception of the shank portion of a screw 29 that is preferably provided with a milled or knurled knob for convenience in loosening or tightening the same. This screw is carried by the lever 18, and when entered in the 15 recess of the link 28, forms a connection between the levers 18 and 23, so that the movement of the upper rock shaft 10 will be transmitted to the blade carrying lever, and the latter will be reciprocated practically in 20 a vertical plane.

Secured to the inner face of the auxiliary frame 15 is a spring tongue 30, having a projecting rib 31, which may enter a recess 32 formed in one face of the knife-carrying 25 lever 18 when the latter has been moved into inoperative position.

In the operation of the device, movement is transmitted from the main shaft to the 30 rock shaft 10, and from thence through the rocker arm 14 and link 24 to lever 23. Movement from the lever 23 is transmitted through the link 28 to the lever 18, and the latter is reciprocated to effect the proper movement of the cutting blade 19.

35 When the trimmer is not required, the screw 29 is loosened, and link 28 is thrown back a trifle, after which the front end of the lever 18 is thrown up, so that the upper knife will be out of the way, the locking 40 lever or projection 31 entering the recess 32 and maintaining the blade carrying lever in its elevated inoperative position.

Having thus described my invention, what I claim as new and desire to secure by Letters Patent, is:—

1. In a trimming device, a supporting frame, a shaft journaled therein, a swinging lever fulcrumed on the shaft, means for operating said lever, a knife-carrying arm 50 fulcrumed on the same shaft, and means for connecting and disconnecting the lever and arm; substantially as described.

2. In a trimming device, a supporting frame, a shaft journaled therein, an angular 55 swinging lever fulcrumed on the shaft and means for operating the same, a knife carrying arm also fulcrumed on the shaft, a knife connected directly thereto and a link for connecting the lever and arm, substantially 60 as described.

3. In a device of the class described, a stationary blade, a movable blade, a loosely mounted laterally moving spring-pressed lever carrying the movable blade, a second 65 loosely mounted laterally moving lever and

means for operating it, and a link connecting the operating lever to the blade carrying lever; substantially as described.

4. In a device of the class described, a stationary blade, a movable blade, a loosely 70 mounted spring-pressed lever carrying said movable blade, an operating lever, and a link, pivoted to the operating lever and detachably connected with the other lever; substantially as described. 75

5. In a device of the class described, a stationary blade, a movable blade, a bracket, a lever pivotally secured on the bracket, and a co-operating yieldingly supported rib or projection and recess located respectively on the 80 bracket and lever for holding said lever in inoperative position, said lever supporting the movable blade.

6. In a device of the class described, a stationary blade, a movable blade, a loosely 85 mounted lever carrying said movable blade and provided with a locking recess, a spring pressed holding rib or projection supported on a stationary part of the machine frame and adapted to enter said recess, and retain 90 the lever in inoperative position, and an operating means to which said lever is detachably connected.

7. The combination with a stationary blade, of a movable blade, a pivot shaft, a 95 frame carrying the same, a lever and a knife-carrying arm both fulcrumed on the shaft, a detachable link connection between the lever and arm, and a spring encircling the shaft and tending to force said lever and arm in 100 the direction of the stationary blade; substantially as described.

8. The combination with a stationary blade, of a movable blade, a pivot shaft, a frame carrying the same, a lever and a 105 knife-carrying arm fulcrumed on the shaft, a detachable link connection between the arm and lever, means for operating the lever, a spring bearing at one end against the lever, and an adjustable stop for the opposite end of said spring; substantially as 110 described.

9. The combination with a stationary blade, a movable blade, a pivot shaft, a frame carrying the same, a lever and a knife 115 carrying arm fulcrumed on the pivot shaft, a detachable link connection between the arm and lever, means for operating the lever, a spring bearing at one end against the lever, and an adjustable stop for the opposite end of said spring, said detachable link connection including a projection on the knife carrying arm and a recess in the link to engage the projection, substantially as 120 described. 125

10. The combination with a frame or bracket, of a shaft supported therein, a stationary blade, a movable blade, an arm pivoted on the shaft and carrying the movable blade, a lever also fulcrumed on the shaft 130

- and connected to the arm, a spring surrounding the shaft and bearing against said lever to hold the blades in contact, a rock shaft, a pair of rocker arms thereon, a link connecting one of the arms to the lever and arranged to permit lateral movement of the latter and means for transmitting movement to the second rocker arm, substantially as described.
- 10 11. The combination with a frame or bracket, of a shaft having spaced supports therein, a hanger connecting the frame to the main frame or gooseneck, a stationary blade adjacent to the needle, a movable blade, an arm pivoted on the shaft and carrying the movable blade, a lever also ful-
- 15

crumed on the shaft and connected to the arm, a spring surrounding the shaft and bearing against said lever to hold the blades in contact, a rock shaft, a pair of rocker 20 arms thereon, a link connecting one of the arms to the lever and arranged to permit lateral movement of the latter, and means for transmitting movement to the second rocker arm; substantially as described. 25

In testimony whereof I affix my signature, in presence of two witnesses.

RUSSEL G. WOODWARD.
